BEVERAGE DISPENSER FAUCET

Louis Gottlieb, 1505-07 Stillman, Philadelphia, Pa.

Filed July 7, 1959, Ser. No. 56,682

Term of patent 14 years

(Cl. D2—3)

Figure 1 is a perspective view of a beverage dispenser faucet showing my new design thereof;

Figure 2 is a side elevational view of the faucet;

Figure 3 is a front elevational view of the faucet;

Figure 4 is a bottom plan view of the faucet; and

Figure 5 is a rear elevational view of the faucet.

The broken line showing of a bracket support and nuts at the rear of the faucet in Figs. 1, 2, 4 and 5 is included for illustrative purposes only.

I claim:

The ornamental design for a beverage dispenser faucet, substantially as shown and described.
